EDGE TRIMMING MACHINE

Harry Keller, Philadelphia, Pa.

Application October 19, 1951, Serial No. 252,030

10 Claims. (Cl. 154—41)

1

This invention relates generally to machines for edging cardboard and similar sheet material and is more particularly concerned with improvements in the class of such machines which fold a continuous tape of binding material about strips of cardboard placed therealong and then sever the tape between the strips of cardboard, the aforementioned improvements affording particular advantage with regard to the spacing and severing operations.

Known machines of the aforementioned class are characterized by automatic feeding of the binding tape, manual feeding of the boards to be bound, and automatic cutoff between the boards fed. These machines have not proved to be entirely satisfactory because the spacing between the boards is determined by the operator as he feeds them into the machine. If they are spaced too far apart, binding tape is wasted; and if they are spaced either too far apart or too close together, the automatic cut off is thrown out of proper timing.

Accordingly, it is an object of this invention to provide a machine for edging cardboard with means for automatically relatively spacing strips of cardboard as they are fed into the machine.

Another object of this invention is to provide such a machine with means for severing the binding tape between the strips of cardboard, such means being automatically operative independently of the length of the cardboard strips and of any spacing therebetween in excess of a minimum predetermined spacing.

Other objects and advantages of the present invention will appear more fully hereinafter, it being understood that the present invention consists in the combination, construction, location and relative arrangement of parts, all as will be more fully described hereinafter, as is shown in the accompanying drawings and will be pointed out in the appended claims.

In the accompanying drawings:

Figure 1 is a perspective view of a machine embodying the present invention, looking toward the front from the left side thereof;

Figure 2 is a sectional elevation along line 2—2 of Figure 1 looking in the direction of the arrows and showing an upper portion of the machine;

Figure 3 is a section along line 3—3 of Figure 4 looking in the direction of the arrows, the cardboard strips being shown.

Figure 4 is a section along line 4—4 of Figure 2 looking in the direction of the arrows, the cardboard strips being omitted for the sake of clarity.

Figure 5 is a perspective view showing the cut

off mechanism, looking toward the rear and from the right side thereof;

Figure 6 is a perspective view taken along line 6—6 of Figure 2;

5 Figure 7 is a perspective view of the machine of Figure 1, looking toward the front from the right side thereof;

Figure 8 is a section along line 8—8 of Figure 7;

10 Figure 9 is a sectional view through the cut off mechanism, looking from the right side thereof and showing the knife in its lowermost position and the binding tape cut.

Figures 10 to 13, inclusive, are sectional views through the cut off mechanism, looking from the left side thereof and showing the associated parts in varying positions as the work is fed through the machine;

15 Figure 14 is a plan view of the binding tape folded about strips of cardboard and ready to be severed;

Figure 15 is a section along line 15—15 of Figure 14;

20 Figure 16 is a section along line 16—16 of Figure 14;

Figure 17 is a diagram showing the electric circuit controlling the cut off mechanism.

25 Figure 18 is similar to Figure 3 but shows the spacing element riding on the upper surface of a cardboard strip being fed through the rollers and another strip in position waiting to follow.

30 The apparatus of the present invention comprises an elongated open frame structure 20 having a front end at which the operator stands to feed the machine, and right and left sides as viewed by the operator from such position. An upper level of the frame structure 20 which is disposed at a convenient working height from floor level mounts a series of roller devices 21 to 26 on longitudinally spaced portions thereof.

35 The roller devices 21 to 26 comprise respectively lower rollers 27 to 32 disposed transversely relative to the longitudinal axis of the machine for rotation respectively in pairs of suitable bearings 33—33 to 38—38 rigidly secured to frame structure 20, each of the rollers having an end portion

40 overhanging the associated bearing and fixedly mounting a chain sprocket 39 and a spur gear 41, the latter being disposed intermediate the chain sprocket 39 and the associated bearing. The several sprockets 39 are disposed for rotation in a common vertical longitudinal plane and have an endless chain 42 trained thereover, excessive slack in the chain 42 being taken up by a plurality of idler sprockets 43 suitably mounted on frame structure 20.

2

The roller devices 21 and 23 to 26 also comprise respectively upper rollers 44 to 48 rotatably mounted in the associated bearings 33—33 and 35—35 to 38—38 and disposed thereby in parallel superimposed relation to the associated lower rollers, each of the upper rollers being downwardly spring pressed and having an end portion overhanging the associated bearing and fixedly mounting a spur gear 49 disposed in meshing engagement with the associated gear 41.

More particularly with regard to rollers 27 and 44, these two rollers have respectively similar opposed reduced portions 51 and 52 intermediate the opposite ends thereof. Mounted on the reduced portion 52 is a collar 53 having an external diameter equal to that of roller 44, and having oppositely facing end surfaces disposed in abutting relation to the opposed sharp shoulders formed by reduced portion 52. The fit of collar 53 on reduced portion 52 and between the sharply defined shoulders formed by the latter is such that due to frictional contact collar 53 will rotate with roller 44 when no resistance is offered to such rotation, but will not turn therewith when any substantial resistance is encountered. Integrally formed with collar 53 and projecting radially outwardly therefrom is a spacing element 54 having opposed outwardly converging surfaces 56 and 57 and oppositely facing side surfaces 58 and 59 set back from the sharply defined shoulders formed by reduced portions 51 and 52, the spacing element 54 being of such a length that it clears reduced portion 51 when collar 53 rotates with roller 44.

Now more particularly with regard to rollers 30 and 46, roller 46 comprises a central shaft 61 mounting a pair of folding disks 62—62 secured in a suitable manner to spaced portions thereof for rotation therewith, and roller 30 comprises a central shaft 63 mounting a pair of folding disks 64—64 on spaced portions thereof for rotation therewith, disks 64—64 being thereby disposed outwardly relative to disks 62—62, and being spring pressed for relative axial movement toward disks 62—62, opposed portions of disks 62—62 and 64—64 being disposed in side abutting relation to one another.

And now more particularly with regard to roller 32, this roller comprises a central shaft 66 having an end portion overhanging the associated bearing 38 and mounting a chain sprocket 39 and a spur gear 41 as already described. In addition, the opposite end portions of shaft 66 fixedly mount respectively a chain sprocket 67 and a handwheel 68, the former being disposed adjacent chain sprocket 39 and the latter being disposed in outer adjacent relation to bearing 38 on the left side of the machine.

Between the floor level and the upper working level of the frame structure 20 is an intermediate level mounting a gluing device toward the rear of the machine. The gluing device comprises a gluing roller 69 disposed transversely relative to the longitudinal axis of the machine and having opposite end portions journaled in bearings 71—71 secured to the frame structure 20. Disposed in parallel rearward adjacent relation to gluing roller 69 is a presser roller 72, which is spring pressed against roller 69. Opposed end portions of rollers 69 and 72 respectively mount meshing spur gears 73 and 74, spur gear 73 also being disposed to mesh with a spur gear 76 secured to a chain sprocket 77 for rotation therewith on a fixed stub shaft 78.

The roller devices 21 to 26 and the gluing de-

vice comprising gluing roller 69 and presser roller 72 are driven in suitably timed relation respectively by endless chains 79 and 81. The endless chain 79 is trained over chain sprocket 67 and a chain sprocket 82, the latter being mounted on a main drive shaft 83, and the endless chain 81 is trained over chain sprocket 77 and a chain sprocket 84, the latter also being mounted on main drive shaft 83, which is driven by a motor 86 through an endless belt drive 87.

On the intermediate level of frame structure 20 and at the rear of the machine is a binding tape reel 88 suitably mounted for rotation about an axis disposed transversely relative to the longitudinal axis of the machine. Just above the intermediate level of frame structure 20 and between reel 88 and presser roller 72 is mounted an idler roller 89 disposed transversely relative to the longitudinal axis of the machine. Another idler roller 91 is similarly mounted at the front of the machine about midway between the upper and intermediate levels of frame structure 20. And still another such roller 92 is similarly mounted on the upper level of frame structure 20 between roller devices 22 and 23. Just above the intermediate level of frame structure 20 and between reel 88 and idler roller 89 is a crossbar 93 disposed transversely relative to the longitudinal axis of the machine. Another crossbar 94 is similarly mounted in the proximity of presser roller 72 in rearward spaced relation thereto. Other crossbars 96 and 97 are disposed in the proximity of gluing roller 69, the former being positioned in close adjacent relation thereto and the latter being positioned in forward spaced relation thereto. And still another crossbar 98 is disposed on the upper level of frame structure 20 between idler roller 92 and roller device 22.

Carried on the upper level of frame structure 20 between roller devices 24 and 25 is a frame 99 mounting a lower guide-bar 101 extending parallel to the longitudinal axis of the machine, and also mounting on each side of the guide bar 101 a set of grooved fold over rollers 102 which are rotatable about vertical axes. An upper guide bar 103 is supported from a bar 104 carried by roller devices 24 and 25 and is disposed thereby in spaced superimposed parallel relation thereto.

Projecting forwardly from the upper level of the frame structure and overhanging the front end thereof is a work feed table 106, and between roller devices 21 and 22 is a guide plate 107 disposed horizontally at about the same level as work feed table 106 and rollers 27 and 28. Supported from roller device 22 in a suitable manner is a guide member 108 provided with a horizontally extending leg disposed in superimposed spaced relation to guide roller 28 and having opposite end portions overhanging roller 28, the rear end portion thereof being disposed over the forward end portion of guide plate 107. At the rear end of the machine a rearwardly and downwardly inclined work receiving table 110 is supported from the frame structure 20, the forward end portion thereof being positioned over reel 88 and the rear end portion being positioned under roller device 26.

On the upper level of frame structure 20 and between roller devices 25 and 26 is a cut off mechanism comprising a frame 109, a knife assembly 111 and control means 112 for the knife. The frame 109 comprises bars 113 and 114 and a pair of similar posts 116—116 all secured together to form a rigid open frame disposed transversely relative to the longitudinal axis of the

machine and in an upright position, bar 113 having opposite end portions thereof rigidly secured to opposed side portions of frame structure 20 and bar 114 being supported in parallel vertically spaced relation thereto by posts 116, the latter being disposed in parallel horizontally spaced relation to one another. In addition, spaced portions of bar 113 between posts 116—116 have a pair of openings formed therein and a pair of tubular sleeves 117—117 terminally rigidly secured thereto over the openings, as by welding, the axes of the openings and of tubular sleeves 117—117 being disposed in parallel vertical relation to one another. Rigidly secured to bar 113 in a suitable manner are additional bars 118 and 119 and plates 121 and 122, all being disposed in side abutting relation to one another and having flush top surfaces, the plate 122 being curved downwardly as best shown in Figure 9. Disposed in a vertical plane parallel to the longitudinal axis of the machine and positioned immediately in advance of the frame 109 is a mounting plate 123 depending from bar 114, the upper end portion of mounting plate 123 being rigidly secured to an intermediate portion of bar 114, in a suitable manner and the lower end portion thereof being disposed just above plate 122.

Within the opening of frame 109 is a cross-head bar 124 having opposite end portions thereof connected to opposite end portions of bar 114 by means of tension springs 126—126, and having a knife 127 secured thereto by bolts 128. Terminally rigidly secured to opposite end portions of crosshead bar 124 and positioned thereby to depend therefrom in parallel relation to one another are a pair of plunger rods 129—129 extending downward through tubular sleeves 117—117 and the associated openings in bar 113.

The control means 112 for the knife comprises a pair of similar electro-magnetic solenoid units 131—131 and a pair of electric switches 132—133 all included in suitable electric circuit, the electric switches 132—133 being actuated respectively by a pair of levers 134—136. The units 131—131 are rigidly secured to the underside of bar 113 by supporting frames 137—137 and are disposed thereby to suitably receive the lower end portions of plunger rods 129—129. The electric switches 132—133 are mounted in close adjacent relation to one another on the right side of an intermediate portion of mounting plate 123, and depending therefrom respectively are elongated flexible members 138—139 having lower end portions mounting respectively rollers 141—142. An elongated adjusting lever 143 is disposed on the left side of the lower end portion of mounting plate 123 and is positioned in side abutting relation thereto, a portion of lever 143 intermediate its ends being secured to the aforementioned lower end portion of mounting plate 123 by bolt 144 for vertical swinging movement of lever 143. Disposed on the right side of the rear end portion of lever 143 and positioned to extend transversely relative to the longitudinal axis of the machine is a pin 146 terminally rigidly secured in place as by welding and having a reduced free end portion 147 forming a sharp shoulder. Mounted on the reduced end portion 147 for pivotal movement about a horizontal axis are levers 134—136 having respectively arms 148—149 extending upwardly from reduced end portion 147, and also having respectively arms 151—152 extending downwardly and rearwardly from reduced end portion 147. Lever 149 is positioned against the sharp shoulder formed by reduced end portion

147 and is disposed thereby to extend upwardly along the right side of mounting plate 123 in spaced relation thereto for engagement with roller 141 of electric switch 132, and lever 148 is positioned alongside lever 149 and extends upwardly for engagement with roller 142 of electric switch 133, the upper extremity of arm 148 being offset to this end from the remainder of lever 148, and levers 148—149 being secured on reduced end portion 147 by a washer 153 and a cotter pin 154. Disposed to extend vertically over the forward end portion of lever 143 is an adjusting screw 156 suitably mounted on plate 123 for relative vertical movement, the lower end portion of adjusting screw 156 being disposed to abut the aforementioned rear end portion. On the right side of mounting plate 123 and disposed in side abutting relation to the lower end portion thereof is a hold down foot 157 having a vertically extending leg portion 158 and a foot portion 159 extending rearwardly therefrom alongside arm 152 of lever 136. The leg portion 158 is provided with a vertically extending slot 161 and is secured to plate 123 by studs 162—162, and the foot portion 159 is provided with a curved bottom edge 163.

A suitable electric circuit for control of the cut off mechanism is shown in Figure 17 wherein switches 132—133 are connected in series and electric-magnetic solenoid units 131—131 are connected in parallel.

The binding tape 164 from reel 88 is passed generally horizontally from the rear to the front of the machine over crossbar 93 and idler roller 89, under crossbar 94, between gluing roller 69 and respectively presser roller 72 and crossbar 95, over crossbar 97 and under idler roller 91. From the latter, tape 164 extends upwardly and rearwardly to the upper level of frame structure 20 where it is passed under crossbar 98 and over idler roller 92. From roller 92, tape 164 is passed horizontally toward the rear of the machine between the rollers of roller devices 23 and 24, between guide bars 101—103 and successive pairs of fold over rollers 102, and between the rollers of roller device 25. From roller device 25 the tape is passed over bars 118—119 and plates 121—122 and under knife 127, arms 151—152 of levers 134—136, and foot portion 159 of hold down foot 157. And finally, the tape is passed through the rollers of the roller device 26.

In the operation of the machine the tape 164 is fed from the reel 88 along the path just outlined, and in this connection it will be noted that the gluing roller 69 has an external surface which is constantly kept moist with glue from a glue pot 166 disposed directly thereunder, the glue being applied to one side of the tape as the latter passes over the gluing roller 69. The operator stands at the front of the machine and feeds similar unbound strips of cardboard 167 from work feed table 196 into roller device 21 from whence they pass between guide plate 197 and guide member 198 and between the latter and roller 23 onto the glued top surface of tape 164 for movement therewith toward the rear of the machine. Roller device 23 presses the cardboard strips 167 down on the glued tape 164, roller device 24 and fold over rollers 102 fold the tape around the strips 167 and roller device 25 presses the folded edges of the tape down on the strips 167.

With regard to the spacing of the strips 167 on the tape 164, the strips are fed from the work feed table 196 into rollers 27 and 44 directly

under collar 53. Since the strips 167 are wider than collar 53, opposite side portions thereof are engaged by rollers 27 and 44, which rotate in opposite directions, as indicated by the arrows in Figure 3, to feed the strips 167 therethrough. As a strip 167 moves away from roller device 21, it leaves collar 53 free to rotate with roller 44, and the then depending spacing element 54 makes roughly three quarters of a revolution before the concave portion of its reversely curved surface 57 strikes the upper surface of another strip 167 which, in the meantime, has been started through rollers 27 and 44, and which prevents collar 53 from rotating further with roller 44. While the strip 167 is being fed through rollers 27 and 44 the spacing element 54 rides on the upper surface thereof, and as the trailing end portion of the strip passes under the spacing element 54, thus freeing collar 53 for rotation with roller 44, the spacing element 54 swings downwardly so that the convex portion of the reversely curved surface 57 at the base of spacing element 54 is disposed in abutting relation to the aforementioned trailing end portion of the strip. Before the spacing element 54 swings downwardly as just mentioned, the leading end portion of another strip 167 is placed over the trailing end portion of the one already being fed through rollers 27 and 44 and is manually pushed to the position shown in Figure 18. As the trailing end portion of the strip 167 already being fed through rollers 27 and 44 leaves work feed table 106 and passes under the spacing element 54, the position of the parts is as shown in Figure 3. It will readily be understood that in swinging downwardly from the position shown in Figure 3, the spacing element 54 acts to space the trailing end portion of one strip 167 from the leading end portion of the next strip 167 a distance equal to the thickness of the spacing element 54 at its base. The operator need only push the latter strip 167 along until it is gripped by the rollers 27 and 44; the spacing between the strips 167 will not depend upon his judgment, but only on the thickness of the spacing element 54 at its base.

When the bound strips of cardboard reach the cut off mechanism the condition of the work is as shown in Figures 14, 15 and 16, and it only remains to sever the tape between the cardboard strips. As the work approaches the knife 127 it is held down by foot 157, which is vertically adjustable through slotted opening 161 engaged by studs 162-162, the lower edge 163 of foot 157 being disposed to engage the upper surface of the cardboard strips. It will be seen that the lower extremities of arms 151-152 of levers 134-136, respectively, are disposed slightly in advance of knife 127, and that the lower extremity of arms 151 is disposed about midway between the lower extremity of arm 152 and knife 127. It will also be seen that the arms 148-149 of levers 134-136 are respectively pressed rearwardly through the action of flexible members 132-133, and that levers 134-136 may be adjusted bodily vertically by manipulating adjusting screw 156.

In the position of the parts shown in Figure 10, hold down foot 157 is engaged with the trailing end portion of one strip of cardboard and the leading end portion of another. Arms 151-152 are both engaged with the upper surface of the aforementioned trailing end portion and arms 148-149 are disposed to incline forwardly. When these arms are thus inclined,

electric switch 132 is open and electric switch 133 is closed. Consequently, as a glance at Figure 17 shows, the electro-magnetic solenoid units 131-131 are de-energized, knife 127 being disposed in raised position.

As the work moves from the position of Figure 10 to that of Figure 11, arm 152 drops from the upper surface of the aforementioned trailing end portion to the upper surface of the tape, 10 and the arm 149 assumes a vertical position, which opens electric switch 133. Since electric switches 132-133 are both open, the electro-magnetic solenoid units are de-energized and knife 127 is still raised.

15 As the work moves from the position of Figure 11 to that of Figure 12, the arm 151 drops from the upper surface of the aforementioned trailing end portion to the upper surface of the tape, 20 and the arm 148 assumes a vertical position, which closes electric switch 132. Since electric switch 132 is now closed and electric switch 133 is open the electro-magnetic solenoid units 131-131 are de-energized and knife 127 is still raised.

25 As the work moves from the position of Figure 12 to that of Figure 13, the arm 152 is raised to engage the upper surface of the aforementioned leading end portion, and the arm 149 is again disposed to incline forwardly, closing electric switch 133. Since electric switches 132-133 are now both closed, the electro-magnetic units 131-131 are energized and act to draw the plunger rods 129 downward against the force of springs 126-126. Of course, the 30 plunger rods carry the crosshead bar 124 and the knife 127 downward, and the latter acts to sever the tape between the cardboard strips, the completed work being moved along by rollers 32-48 and delivered to work receiving table 119.

40 As the work moves along from the position of Figure 13 to that of Figure 10, the arm 151 is raised to engage the upper surface of the aforementioned leading end portion, and the arm 148 again assumes a forwardly inclined position, opening electric switch 132. Since electric switch 132 is now open and electric switch 133 is closed, the electro-magnetic solenoid units 131-131 are de-energized and the knife 127 is raised again by the action of springs 126-126.

50 It will be noted that the electro-magnetic solenoid units 131-131 are energized during the period of time that arm 152 is lifted by the leading end of the strip 167, while arm 151 remains lowered in engagement with the relatively 55 thin tape portion extending between adjoining cardboard strips, this being one of the important factors to be considered in timing the machine for proper operation. Other such factors are the time it takes for the knife to move 60 from its raised to its cutting position, the rate of feed through the machine, and the spacing between the cardboard strips. All the factors controlling the timing may be correlated so that the knife will be lowered to cut the tape between 65 the cardboard strips at a predetermined distance from the leading end portion of the cardboard strip approaching knife 127.

It should be apparent now that a machine for 70 edging cardboard strips has been provided with automatic means independent of the operator's judgment for relatively spacing strips of cardboard along a continuous binding tape as the cardboard strips are fed into the machine for binding. And it should be apparent that such a machine has been provided with means for

severing the tape between the strips of cardboard, and that the means provided is operative independently of the length of the strips fed through the machine, and is also operative independently of any spacing of said strips in excess of a minimum predetermined spacing.

Although the apparatus herein disclosed as embodying the invention has particular utility in the construction of machines for edging cardboard strips, certain features are of more general application and, therefore, it is not intended to limit the invention to the exact construction and combination herein shown and described for purposes of illustration as various modifications within the scope of the appended claims may occur to persons skilled in the art.

What is claimed as new and useful is:

1. In a machine for edging cardboard strips with a binding tape, said machine comprising a supporting frame structure, means on said frame structure for feeding a continuous strip of said binding tape along a predetermined path in one direction at a predetermined rate, and means on said frame for successively feeding said cardboard strips into the path of said tape at said predetermined rate and positioning said cardboard strips along said tape in predetermined spaced relation to one another for movement therewith in the same direction, said last mentioned means comprising a pair of roller elements carried by said frame structure and mounted for rotation about parallel axes in opposite directions for engaging the oppositely facing surfaces of a portion of said cardboard strips to feed said cardboard strips therethrough, and a separator element extending generally radially from the axis of one of said roller elements and beyond the periphery thereof, said separator element being positionable between the opposed end portions of successive leading and trailing cardboard strips, and said separator element being mounted for rotation with the associated one of said roller elements through frictional contact therewith, being thus rotated from said position between the opposed end portions of said leading and trailing cardboard strips to a position wherein said separator element rests upon an intermediate portion of said trailing cardboard strip whereby said separator element is restrained from further rotation with said associated roller element and held in readiness to follow said trailing cardboard strip when released from said restraint for separating the latter from the next succeeding cardboard strip, and means for cutting said tape between said cardboard strips.

2. In a machine for edging cardboard strips with a binding tape, said machine comprising a supporting frame structure, means on said frame structure for feeding a continuous strip of said binding tape along a predetermined path in one direction at a predetermined rate, and means on said frame for successively feeding said cardboard strips into the path of said tape at said predetermined rate and positioning said cardboard strips along said tape in predetermined spaced relation to one another for movement therewith in the same direction, said last mentioned means comprising a pair of elongated rollers mounted on said frame structure for rotation about parallel axes in opposite directions, said rollers having opposed reduced portions intermediate the ends thereof, the opposed shoulders of said rollers formed by said reduced portions being disposed to engage oppositely facing side surfaces of said cardboard strips to feed said cardboard strips through said rollers, a collar relatively rotatably mounted on said reduced portion of the upper roller, the oppositely facing side surfaces thereof being disposed in frictional contact with the shoulders formed by said reduced portion of the upper roller, and a separator element carried by said collar and extending generally radially therefrom, said separator element having a pair of oppositely facing side surfaces disposed in inwardly spaced relation to the shoulders formed by said reduced portion of the lower roller, and having a second pair of oppositely facing surfaces converging outwardly to an end portion disposed to clear said reduced portion of the lower roller, said separator element being positionable between the opposed end portions of successive leading and trailing cardboard strips, said collar being mounted for rotation with said upper roller through said frictional contact therewith, and said separator element being thus rotated from said position between the opposed end portions of said leading and trailing cardboard strips to a position wherein said separator element engages the upper surface of said trailing cardboard strip whereby said separator element is restrained from further rotation with said upper roller and held in readiness to follow said trailing cardboard strip when released from said restraint for separating the latter from the

tions of said cardboard strips to feed said cardboard strips through said rollers, a collar relatively rotatably mounted on the reduced portion of one of said rollers, and a separator element carried by said collar and extending generally radially therefrom beyond the periphery of the associated roller, said separator element being positionable between the opposed end portions of successive leading and trailing cardboard strips, said collar being mounted for rotation with said associated roller through frictional contact therewith, and said separator element being thus rotated from said position between the opposed end portions of said leading and trailing cardboard strips to a position wherein said separator element rests upon an intermediate portion of said trailing cardboard strip whereby said separator element is restrained from further rotation with said associated roller and held in readiness to follow said trailing cardboard strip when released from said restraint for separating the latter from the next succeeding cardboard strip, and means for cutting said tape between said cardboard strips.

3. In a machine for edging cardboard strips with a binding tape, said machine comprising a supporting frame structure, means on said frame structure for feeding a continuous strip of said binding tape along a predetermined path in one direction at a predetermined rate, and means on said frame for successively feeding said cardboard strips into the path of said tape at said predetermined rate and positioning said cardboard strips along said tape in predetermined spaced relation to one another for movement therewith in the same direction, said last mentioned means comprising a pair of elongated rollers mounted one above the other on said frame structure for rotation about horizontal parallel axes in opposite directions, said rollers having opposed reduced portions intermediate the ends thereof, the opposed shoulders of said rollers formed by said reduced portions being disposed to engage oppositely facing side portions of said cardboard strips to feed said cardboard strips through said rollers, a collar relatively rotatably mounted on said reduced portion of the upper roller, the oppositely facing side surfaces thereof being disposed in frictional contact with the shoulders formed by said reduced portion of the upper roller, and a separator element carried by said collar and extending generally radially therefrom, said separator element having a pair of oppositely facing side surfaces disposed in inwardly spaced relation to the shoulders formed by said reduced portion of the lower roller, and having a second pair of oppositely facing surfaces converging outwardly to an end portion disposed to clear said reduced portion of the lower roller, said separator element being positionable between the opposed end portions of successive leading and trailing cardboard strips, said collar being mounted for rotation with said upper roller through said frictional contact therewith, and said separator element being thus rotated from said position between the opposed end portions of said leading and trailing cardboard strips to a position wherein said separator element engages the upper surface of said trailing cardboard strip whereby said separator element is restrained from further rotation with said upper roller and held in readiness to follow said trailing cardboard strip when released from said restraint for separating the latter from the

next succeeding cardboard strip, and means for cutting said tape between said cardboard strips.

4. In a machine for edging cardboard strips with a binding tape, said machine comprising a supporting frame structure, means on said frame structure for feeding a continuous strip of said binding tape along a predetermined path in one direction at a predetermined rate, means on said frame for successively feeding said cardboard strips into the path of said tape at said predetermined rate and positioning said cardboard strips along said tape in predetermined spaced relation to one another for movement therewith in the same direction, and means for cutting said tape comprising a knife mounted on said frame structure and movable for cutting said tape, a pair of arms disposed to engage spaced portions along said tape and cardboard strips, each arm being movable independently of the other between one position wherein it directly engages a cardboard strip and another position wherein it directly engages the tape between two successive cardboard strips, said arms successively assuming a plurality of different relative positions as said tape and cardboard strips pass thereby in contact therewith, and said knife being actuated in response to one of said different relative positions of the arms for cutting said tape between said cardboard strips.

5. In a machine for edging cardboard strips with a binding tape, said machine comprising a supporting frame structure, means on said frame structure for feeding a continuous strip of said binding tape along a predetermined path in one direction at a predetermined rate, means on said frame for successively feeding said cardboard strips into the path of said tape at said predetermined rate and positioning said cardboard strips along said tape in predetermined spaced relation to one another for movement therewith in the same direction, and means for cutting said tape comprising a knife mounted on said frame structure and movable for cutting said tape, a pair of arms disposed to engage spaced portions along said tape and cardboard strips, each arm being movable independently of the other between one position wherein it directly engages a cardboard strip and another position wherein it directly engages the tape between two successive cardboard strips, said arms successively assuming a plurality of different relative positions as said tape and cardboard strips pass thereby in contact therewith, a pair of electric switches each arranged to close and open independently of the other in response to the movement of one of said arms, both of said electric switches being closed when said arms assume one of said different relative positions and either or both being open when said arms are in any other one of said different relative positions, and electro-magnetic solenoid means connected in electric circuit with said electric switches, the last mentioned means being energized when both of said electric switches are closed, and said knife being actuated thereby for cutting said tape between said cardboard strips.

6. In a machine for edging cardboard strips with a binding tape, said machine comprising a supporting frame structure, means on said frame structure for feeding a continuous strip of said binding tape along a predetermined path in one direction at a predetermined rate, means on said frame for successively feeding said cardboard strips into the path of said tape at said predetermined rate and positioning said cardboard

strips along said tape in predetermined spaced relation to one another for movement therewith in the same direction, and means for cutting said tape comprising a knife yieldably suspended from said frame structure and disposed thereby over said tape, a pair of elongated levers having intermediate portions pivotally connected to said frame structure for swinging movement of said levers about a horizontal axis, said levers being disposed thereby above said tape and in longitudinally spaced relation to said knife, and each of said levers comprising an upright arm and an angularly related lower arm extending downward and toward said knife from said intermediate portion, the terminal portions of said lower arms being relatively longitudinally spaced and disposed to engage spaced portions along said tape and cardboard strips, each of said levers being movable independently of the other between one position wherein said terminal portion of the associated lower arm directly engages a cardboard strip and another position wherein said terminal portion directly engages the tape between two successive cardboard strips, said levers successively assuming a plurality of different relative positions as said tape and cardboard strips pass thereunder in contact therewith, a pair of electric switches each arranged to close and open independently of the other in response to the movement of one of said upright arms of the levers, both of said electric switches being closed when said levers assume one of said different relative positions and either or both being open when said levers are in any other one of said different relative positions, and electro-magnetic solenoid means connected in electric circuit with said electric switches, the last mentioned means being energized when both of said electric switches are closed, and said knife being actuated thereby for cutting said tape between said cardboard strips.

7. A device for cutting a continuous tape between cardboard strips carried thereby in spaced relation to one another, a supporting frame structure, a knife mounted on said frame structure and movable for cutting said tape, a pair of arms disposed to engage spaced portions along said tape and cardboard strips, each arm being movable independently of the other between one position wherein it directly engages a cardboard strip and another position wherein it directly engages the tape between two successive cardboard strips, said arms successively assuming a plurality of different relative positions as said tape and cardboard strips pass thereby in contact therewith, a pair of electric switches each arranged to close and open independently of the other in response to the movement of one of said arms, both of said electric switches being closed when said arms assume one of said different relative positions and either or both being open when said arms are in any other one of said different relative positions, and electro-magnetic solenoid means connected in electric circuit with said electric switches, the last mentioned means being energized when both of said electric switches are closed, and said knife being actuated thereby for cutting said tape between said cardboard strips.

8. A device for cutting a continuous tape between cardboard strips carried thereby in spaced relation to one another, a supporting frame structure, a knife yieldably suspended from said frame structure and disposed thereby over said tape, a pair of elongated levers having inter-

mediate portions pivotally connected to said frame structure for swinging movement of said levers about a horizontal axis, said levers being disposed thereby above said tape and in longitudinally spaced relation to said knife, and each of said levers comprising an upright arm and an angularly related lower arm extending downward and toward said knife from said intermediate portion, the terminal portions of said lower arms being relatively longitudinally spaced and disposed to engage spaced portions along said tape and cardboard strips, each of said levers being movable independently of the other between one position wherein said terminal portion of the associated lower arm directly engages a cardboard strip and another position wherein said terminal portion directly engages the tape between two successive cardboard strips, said levers successively assuming a plurality of different relative positions as said tape and cardboard strips pass thereunder in contact therewith, a pair of electric switches each arranged to close and open independently of the other in response to the movement of one of said upright arms of the levers, both of said electric switches being closed when said levers assume one of said different relative positions and either or both being open when said levers are in any other one of said different relative positions, and electro-magnetic solenoid means connected in electric circuit with said electric switches, the last mentioned means being energized when both of said electric switches are closed, and said knife being actuated thereby for cutting said tape between said cardboard strips.

9. In a machine for edging cardboard strips with a binding tape, said machine comprising means for feeding a continuous strip of said binding tape along a predetermined path in one direction at a predetermined rate, means for successively feeding said cardboard strips into the path of said tape at said predetermined rate and positioning said cardboard strips along said tape in predetermined spaced relation to one another for movement therewith in the same direction, and means for cutting said tape comprising a knife, a pair of arms disposed to engage spaced portions along said tape and cardboard strips, each arm being movable independently of the other between one position wherein it directly engages a cardboard strip and another position wherein it directly engages the tape between two successive cardboard strips, said arms successively assuming a plurality of

different relative positions as said tape and cardboard strips pass thereby in contact therewith, a pair of electric switches each arranged to close and open independently of the other in response to the movement of one of said arms, both of said electric switches being closed when said arms assume one of said different relative positions and either or both being open when said arms in any other one of said different relative positions, and electro-magnetic solenoid means connected in electric circuit with said electric switches, the last mentioned means being energized when both of said electric switches are closed, and said knife being actuated thereby for cutting said tape between said cardboard strips.

10. A device for cutting a continuous tape between cardboard strips carried thereby in spaced relation to one another, a knife movable for cutting said tape, a pair of arms disposed to engage spaced portions along said tape and cardboard strips, each arm being movable independently of the other between one position wherein it directly engages a cardboard strip and another position wherein it directly engages the tape between two successive cardboard strips, said arms successively assuming a plurality of different relative positions as said tape and cardboard strips pass thereby in contact therewith, a pair of electric switches each arranged to close and open independently of the other in response to the movement of one of said arms, both of said electric switches being closed when said arms assume one of said different relative positions and either or both being open when said arms are in any other one of said different relative positions, and electro-magnetic solenoid means connected in electric circuit with said electric switches, the last mentioned means being energized when both of said electric switches are closed, and said knife being actuated thereby for cutting said tape between said cardboard strips.

HARRY KELLER.
